(57) **CLAIM**

We claim the ornamental design for an inner cover for door of washing machine, as shown and described.

DESCRIPTION

FIG. 1 is a front perspective view of an inner cover for door of washing machine showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front perspective view thereof;

FIG. 9 is a rear perspective view thereof;

FIG. 10 is an enlarged view of the encircled portion 10 in FIG. 2; and,

FIG. 11 is another rear perspective view of the inner cover for door of washing machine in which a washing machine is provided in dot-dash broken lines to illustrate an example environment.

The short dash-dot broken line in the figures show unclaimed portions of the inner cover for door of washing machine, the dot-dash broken line in FIG. 11 is for illustrating environmental structure, and the dot-dot-dash broken line encircling portions of the claimed design in FIGS. 2 and 10 is for illustrating enlargements; the broken lines form no part of the claimed design.
